UNITED STATES PATENT OFFICE

100,802

DESIGN FOR AN AUTOMOBILE HEATER

Philmore F. Sperry, Chicago, Ill.

Application June 1, 1936, Serial No. 62,923

Term of patent 7 years

To all whom it may concern:

Be it known that I, Philmore F. Sperry, a citizen of the United States, residing at Chicago, in the county of Cook and State of Illinois, have invented a new, original, and ornamental Design for Automobile Heaters, of which the following is a specification, reference being had to the accompanying drawing, forming part thereof.

Fig. 1 is a perspective view of an automobile heater, showing my new design;

Fig. 2 is a front view of the heater; and

Fig. 3 is a side view of the heater.

I claim:

The ornamental design for an automobile heater as shown.

PHILMORE F. SPERRY.
